UNITED STATES PATENT OFFICE

HERMAN HERRENBRUCK, OF BELLEVILLE, ILLINOIS, ASSIGNOR TO OREON STOVE CO.,
OF BELLEVILLE, ILLINOIS, A CORPORATION OF DELAWARE

STOVE

Application filed June 14, 1928. Serial No. 285,245.

This invention relates to heating stoves of the type in which a stove is mounted in a supporting and enclosing casing into which the air is admitted to be heated by the stove and 5 from which the heated air passes to the outside of the casing.

An object of the invention is to provide improved means for controlling the circulation of the air into and from the casing in 10 which the stove proper is enclosed.

Another object of the invention is to provide means within the casing for damping or baffling the ascent of the heated air within the casing so as to regulate and control the 15 circulation.

Another object of the invention is to provide a casing for enclosing a stove proper and provided with louvres in the walls, in combination with damping or baffling devices 20 movable to positions between the stove proper and the walls of the casing containing the louvres so as to prevent the rapid ascent of air between the stove proper and the casing walls having the louvres, thus retarding and 25 deflecting the heated air through the louvres and closer to the floor of the room containing the stove.

Other objects will appear from the following description, reference being made to the 30 drawing in which—

Fig. 1 is a vertical sectional view of a stove embodying the present invention and looking toward the inside of the rear wall of the casing.

Fig. 2 is a view looking toward one of the lateral side walls of the casing showing the arrangement of one of the louvres.

Fig. 3 is a perspective view of one of the guard devices for protecting the casing walls 40 from the intense heat of the enclosed stove.

Fig. 4 is an enlarged sectional view, on the line 4—4 of Fig. 2, showing the louvre construction.

The front wall and doors of the casing are 45 omitted from the drawing, as illustration of these features is not necessary to a complete understanding of the present invention. The rear wall 1 and the lateral side walls 2 are attached to a rigid lower end frame 3 and, 50 together with the front wall and doors (not

shown) and the top wall 4, form the exposed part of the casing which is supported by legs 5. The upper portion of the rear wall 1 has an opening 6 formed through it to accommodate a stove pipe extending from the stove 7 55 enclosed within the casing. The opening 6 is surrounded by an inwardly extending marginal flange 8 which reinforces and strengthens the adjacent wall structure. The upper end wall 4 is provided with a number of bosses 60 or thickened portions 9 which seat upon flanges 10 formed by inwardly extended portions of the casing walls. Screws 11 pass through the wall flanges 10 and engage within the bosses 9, thus rigidly securing the top 65 wall in connection with the vertical casing walls.

Each of the lateral side walls 2 is protected from the intense heat of the stove 7 by a liner device. The liner device for each of the walls 70 2 comprises a metallic plate 12 having a sheet 13 of heat insulating material, such as asbestos, attached to its outer side. These liners are supported from the flanges 10 by hooks 14 attached to the liners and engaging the 75 flanges and are held in spaced relationship from the adjacent walls 2 by vertical channel members 15 and angular arms 16. The channel members 15 are attached to the liners and have their flanges extending outwardly toward the walls 2 with which said flanges may contact. The arms 16 are attached to the plates 12 and are of angular formation so that they engage with the walls 2.

Each of the walls 2 is provided with a 85 louvre window which may be made by splitting said walls horizontally and downwardly at the ends of the horizontal splits and bending inwardly the parts 17 defined by the splits and forming louvre boards or slats. While 90 these louvre boards or slats 17 are shown as formed integral with the walls 2 it is obvious that they may be arranged otherwise, if desired.

The lower edges of the liners for the lateral side walls 2 terminate approximately as shown in the plane of the upper ends of the louvres, though this arrangement may be varied, if desired, without departure from the principle of the invention. 100

For the rear casing wall 1, I provide a similar liner similarly supported and provided at its upper end with a notch 18 to receive the stove pipe or flue. The liner for the rear wall 5 extends downwardly to a considerable distance below the lower ends of the liners for the lateral side walls and terminates above the air inlet openings 19.

My invention comprises a damper or baffle 10 for controlling and regulating the ascent of the air entering the casing through the open lower end frame and through the louvres and through the holes 19. These dampers or baffles may be supported as desired and, as 15 shown, said dampers or baffles comprise a pair of plates 20 mounted on horizontal pivots 21 in connection with the sides of the stove 7 toward the louvre walls 2. A feature is that the plates 20 are supported by the stove 20 proper and not by the casing. From one of these dampers or baffles 20 a chain 22 extends over supports 23 and thence outwardly through an opening 24 in the top wall 4 for manual engagement and operation. From 25 the other damper or baffle 20 a chain 25 extends to sliding connection 26 with the chain 22 so that by drawing the chain 22 taut both dampers or baffles 20 will be moved to approximately horizontal positions in which 30 their outer edges are close to the louvre walls 2 and near the upper ends of the louvre. This prevents too rapid circulation of the air through the casing by retarding and baffling movement of the air entering the casing, so 35 that the air is retained in the casing for a longer duration and becomes heated to a greater degree. However, the heated air is permitted to rise at the front and rear of the stove 7 and to pass out through the perforated top wall 4.

From the foregoing it will be seen that while the air may freely enter the casing it does not freely pass to the top of the casing at the lateral sides of the stove proper. A 45 part of the heated air is deflected outwardly and downwardly because of the proximity of the louvre to the dampers 20; and the dampers or baffles 20 retard ascent of the air until the air is properly heated so that a 50 room may be more quickly and satisfactorily heated than if cold air were permitted to circulate through the stove casing.

The construction and arrangement of my improved stove may be varied within equivalent limits and in other respects than those 55 specially mentioned. I contemplate such variations as may be found desirable or expedient and do not restrict myself unconditionally in any respect.

I claim:

1. A fuel burning stove, a casing enclosing 60 said stove and having louvres in the walls thereof, liners supported within said casing and spaced from said stove and said casing, 65 the spaces between said liners and said casing

being open at their lower ends, and damper elements supported within said casing for retarding the ascent of air entering said casing through said louvres and into the lower ends of said spacing.

2. A fuel burning stove including a rear wall and side walls, louvres in said side walls, liners supported between said side walls and said stove and having their lower ends near and spaced inwardly from the upper ends of 70 said louvres, and a liner between said stove and said rear wall and extending below the lower ends of said first named liners.

3. A fuel burning stove including a rear wall and side walls, louvres in said side walls, liners supported between said side walls and said stove and having their lower ends near and spaced inwardly from the upper ends of 75 said louvres, a liner between said stove and said rear wall and extending below the lower ends of said first named liners, and damper devices supported within said casing for retarding and controlling the ascent of air between 80 said stove and said side walls.

4. A fuel burning stove including a rear wall and side walls, louvres in said side walls, liners supported between said side walls and said stove and having their lower ends near and spaced inwardly from the upper ends of 85 said louvres, a liner between said stove and said rear wall and extending below the lower ends of said first named liners, damper devices supported within said casing for retarding and controlling the ascent of air between 90 said stove and said side walls, and means moving said damper devices to positions extending approximately horizontally from said stove to said side walls.

5. A fuel burning stove including a rear wall and side walls, louvres in said side walls, liners supported between said side walls and said stove and having their lower ends near and spaced inwardly from the upper ends of 95 said louvres, a liner between said stove and said rear wall and extending below the lower ends of said first named liners, damper devices supported within said casing for retarding and controlling the ascent of air between 100 said stove and said side walls, and means moving said damper devices to positions extending approximately horizontally from said stove to said side walls below the ends of said first named liners.

6. A fuel burning stove, a casing enclosing 105 said stove including side walls having louvres and a rear wall, damper elements pivotally supported in said casing for controlling and regulating the ascent of air in 110 said casing between said stove and said side walls, and a liner supported in said casing and spaced from said rear wall and extending 115 downwardly below the planes of said damper elements.

7. A fuel burning stove and an enclosing 120 casing therefor having walls spaced from said 125

stove, damper devices pivoted to said stove in said casing for controlling the ascent of air in said casing between the walls of said casing and said stove, and means for simultaneously operating said damper devices to position to control the ascent of air in said casing.

8. A stove for the combustion of fuel, a casing enclosing said stove and having louvres in the lateral walls thereof, damper elements having their inner edges hinged to said stove approximately in the plane of the upper portions of said louvres, said damper elements being arranged to be moved downwardly to open position by gravity, and means for swinging the free edges of said damper elements upwardly and outwardly toward said casing to retard the ascent of air above said louvres between said stove and the walls containing said louvres.

9. A stove for combustion of fuel, a casing enclosing said stove and having louvres in the lateral walls thereof, damper elements, and pivots supporting the inner edges of said damper elements in connection with said stove and permitting said damper elements to be suspended vertically below said pivots and to be moved upwardly and outwardly to positions in which the outer edges of said damper elements are adjacent to said casing near the upper ends of said louvres to retard the ascent of air above said louvres between said stove and the walls containing said louvres.

35 10. A stove for combustion of fuel, a casing enclosing said stove and having louvres in the lateral walls thereof, damper elements, pivots supporting the inner edges of said damper elements in connection with said stove and permitting said damper elements to be suspended vertically below said pivots and to be moved upwardly and outwardly to positions in which the outer edges of said damper elements are adjacent to said casing near the upper ends of said louvres to retard the ascent of air above said louvres between said stove and the walls containing said louvres, and means for moving said damper elements to and supporting said damper elements in said positions to retard the ascent of air as aforesaid.

11. A stove for the combustion of fuel, a casing enclosing said stove and having an open lower end and having openings in its rear side near its lower end and having louvres in its lateral sides above the plane of said openings, a plate supported between said stove and said rear wall of said casing and spaced from both and having its lower end above said openings, a plate supported between said stove and each of said lateral side walls of said casing and spaced both from said stove and from said lateral side walls of said casing and having its lower end above said louvres, damper elements hinged to said

stove between said first-named plate and the front of the casting approximately in the plane of the upper portions of said louvres and being moved downwardly to open position by gravity, and means for swinging the free ends of said dampers upwardly and outwardly to said lateral side walls of said casing and below said second-named plates to retard the ascent of air above said louvres between said stove and said walls containing said louvres.

12. A stove for the combustion of fuel, a casing enclosing said stove and having an open lower end and having openings in its rear side near its lower end and having louvres in its lateral sides above the plane of said openings, a plate supported between said stove and said rear wall of said casing and spaced from both and having its lower end above said openings, a plate supported between said stove and each of said lateral side walls of said casing and spaced both from said stove and from said lateral side walls of said casing and having its lower end above said louvres, damper elements, pivots supporting the inner edges of said damper elements in connection with said stove and permitting said damper elements to be suspended vertically below said pivots and to be moved upwardly and outwardly to positions in which the outer edges of said damper elements are below the lower ends of said second-named plates and are adjacent to said lateral side walls of said casing near the upper ends of said louvres, and means for moving said damper elements to and supporting said damper elements in said positions.
